[57] ABSTRACT

Shaft means is mounted upon a base and supports a plurality of adjacent plate members for rotation around the axis of said shaft. Said plate members define substantially identical and regular polygons circumscribed by identical circles coaxial with said shaft axis. Plural rolls of tape having coaxial openings with diameters substantially identical to the diameters of said circumscribed circles can be sleeved over said plate members for separate, independent rotation. A cutting edge is mounted upon the base for severing portions of the tape from the rolls thereof.

TAPE DISPENSER FOR MULTIPLE ROLLS

BACKGROUND OF THE INVENTION

This invention relates in general to a device for supporting rolls of material and dispensing parts from said rolls and, more particularly, to a device which supports said rolls so that they can rotate completely independently one from the other even though they are rotating around a common axis and are positioned closely adjacent to each other.

Persons familiar with the continuing demand for means of dispensing materials from plural rolls thereof, such as rolls of Christmas wrapping tape of various colors, sizes and types, have long recognized the need for a dispensing device capable of supporting the various rolls for completely independent rotation. Existing devices for dispensing materials from rolls fall into two general categories, namely, those in which the roll supports are not readily adaptable to the varying roll widths and those which have a single roll support so that all rolls tend to rotate when one is rotated for the purpose of dispensing the tape therefrom. In other words, the user must choose between a dispenser upon which the rolls of specific axial sizes must be used, in order to get independent roll rotation, or a substantially single roll support which tends to rotate all rolls when one is rotated.

Elaborate attempts have been made in the past to overcome this problem. For example, alternate roll support members have been furnished with the dispenser so that many variations in axial roll dimension could be accommodated. However, this necessitated the storage of such extra rollers and additional expense.

Another serious problem confronting the mounting of plural adjacent rolls of strip material on a single existing dispenser involves the severing of the tape from the roll. Where three or more rolls are coaxially supported adjacent to each other, the strip of tape on at least one roll is located between two other strips and, accordingly, is at least difficult to grasp. Often an attempt to grasp the middle strip results in tangling or snarling the adjacent strips and this can be extremely inconvenient during a package-wrapping operation involving strips coated with an adhesive.

Accordingly, a primary object of this invention is the provision of a device for rotatably supporting plural, axially adjacent rolls of material so that each roll can rotate completely independently of adjacent rolls, said device having means for severing parts of the material from the remainder thereof on the rolls.

A further object of this invention is the provision of a dispensing device, as aforesaid, which is able to accommodate rolls of any axial dimension within the limits of the maximum length of the roll-supporting mechanism, which permits rotation of said rolls so that the material thereon can be readily and easily dispensed by a cutting edge, which can be manufactured inexpensively and upon which rolls of different axial lengths can be quickly mounted or removed without any adjustment in the dispenser.

Other objects and purposes of this invention will become apparent to persons familiar with this type of equipment upon reading the following descriptive material and examining the accompanying drawings, in which:

FIG. 1 is a perspective view of a dispenser embodying the invention.

FIG. 2 is a broken, top plan view of said dispenser.

FIG. 3 is a sectional view taken along the line III—III in FIG. 2.

FIG. 4 is a side-elevational view of a modified dispenser embodying the invention.

FIG. 5 is a broken, front view of said modified dispenser.

FIG. 6 is a sectional view taken along the line VI—VI in FIG. 5.

For convenience in description, the terms "upper," "lower," "front," "rear" and words of similar import will have reference to the dispenser of the invention when located in its normal position of operation, FIG. 2 illustrating the top of the

dispenser, the front of which is at the left end of the view. The words "inner," "outer" and derivatives thereof will have reference to the geometric center of the dispenser and principal parts thereof.

SUMMARY OF THE INVENTION

The objects and purposes of the invention, including those set forth above, have been met by providing a dispenser having a base-supporting shaft means upon which a plurality of identical, adjacent plate members are supported for coaxial rotation. Said plate members are circumscribed by identical circles coaxial with the shaft means so that plural rolls of material having openings equal to said circles can be sleeved upon the plate members and each roll is rotatable around said shaft means independently of adjacent rolls. A cutting edge is mounted upon the base means for severing portions of the material from the rolls.

DETAILED DESCRIPTION

The dispenser 10 (FIG. 1) has a substantially channel-shaped base 11 including a front flange 12, a rear flange 13 and a supporting web 14 therebetween. A pair of integral, parallel and spaced arms 16 and 17 project frontwardly from the opposite ends of the upper edge of the rear flange 13 to a line approximately midway between the upper edges of the front and rear flanges.

A pair of U-shaped clips 18 and 19 (FIG. 2) are mounted upon the front ends of the arms 16 and 17, respectively. Specifically, the clip 19 has a lower leg 22 which extends along the lower surface of the front end of the arm 17 and is rigidly secured thereto by the rivet 23. The upper leg 24 of the clip 19 is spaced above the arm 17 and is arcuate, the concave surface thereof facing downwardly. The rearward edge of the upper leg 24 may be flared upwardly to facilitate entry of the adjacent end of the shaft 26 between the upper leg 24 and the arm 17.

The clip 18 (FIG. 3) has lower and upper legs 22A and 24A, respectively, and the adjacent end of the shaft 26 can be yieldably held between the upper leg 24A and the arm 16.

The shaft 26, which is removably held within the clips 18 and 19, has a transverse pin 27 extending through and beyond both sides thereof. The front side 28 of the clip 19, which extends between the legs 22 and 24 thereof, has an opening 29 into which one end of the pin 27 can be received. The pin 27 positively opposes rotation of the shaft 26 relative to the clips 18 and 19, hence the base 11.

A plurality of roll-supporting plate members 32 have central openings 33 (FIG. 2) through which the shaft 26 is snugly but rotatably received. Each plate member 32 is preferably identical with every other plate member and preferably has the peripheral shape of a regular polygon, here a hexagon. Each plate member is circumscribed by an imaginary circle concentric with the shaft 26 and preferably substantially identical with the diameter of the center opening 34 in each roll 36 supported by the dispenser 10. In this embodiment, each plate member is separated from the next by an annular spacer 37, such as a washer, which rotatably encircles the shaft 26. The spacers 37 may be independent of the plate members or secured to one of the adjacent plate members which it separates. However, the arrangement is loose to avoid induced rotation between adjacent plate members.

While plate members 32 of identical shape and size are disclosed for illustrative purposes, it will be recognized that, for example, the plate members at one end of the shaft 26 might be substantially larger, while being of uniform circumscribed size, than the plate members at the other end of the shaft 26 so that rolls having central openings of different sizes can be mounted upon and supported by the same dispenser. Also, as long as the plate members have the same circumscribed size, they may be comprised of different or even irregular polygons. Moreover, plate members having just two points of contact with a said roll may be used, particularly where the roll encircles several plate members.

A cutting blade 38 having a serrated cutting edge 39 is mounted upon the upper end of the front flange 12 by means of screws 42. The cutting edge 39 is preferably parallel with the shaft 26 and spaced therefrom a distance sufficient to avoid interference thereby with the rotation of the rolls 36. The cutting edge 39 is arranged to be engaged by the strips 43 to sever portions thereof from the rolls 36.

FIG. 3 illustrates modified plate members 46 interleaved, alternately, with plate members 32A, which may be identical with the plate members 32 in FIG. 2. The modified plate members 46 have projections 47 on both sides thereof for engaging the plate members 32A adjacent thereto and thereby spacing adjacent plate members 46 and 32A from each other. The projections 47 are preferably arranged along a circle concentric with the shaft 26 (FIG. 4) to avoid wobbling.

The dispenser 51 illustrated in FIGS. 4, 5 and 6 may be identical with the dispenser 10 except for the auxiliary cutting blade 52 mounted upon the front flange 12A above the cutting blade 38A by means including the front and rear support plates 53 and 54. The cutting blade 52 has a cutting edge 56 which is preferably parallel with and is spaced from the cutting edge 39A. The cutting edge 56 (FIG. 5) is aligned radially with one of the rolls 36 whereas the cutting edge 56 is aligned with an adjacent roll 36. Thus, as shown in FIG. 4, the strip from either roll can be grasped with ease and without being obstructed by the strip from the other roll.

OPERATION

The operation of the dispenser described above will be apparent to persons skilled in this art upon reading such description. However, for convenience, the operation will be summarized hereinafter.

Since the plate members 32 (FIG. 2) or 32A and 46 (FIG. 3) can be provided in various diametrical sizes, such sizes will be governed by the diameter of the center openings 34 in the rolls 36 to be mounted upon said plate members. Accordingly, when plate members of the appropriate size are mounted upon the shaft 26, the roll or rolls of strip material can be sleeved upon the plate members 32 or 32A and 46 as appearing in FIGS. 2 and 3, respectively.

The plate members 32 (FIG. 1), for example, can be randomly positioned circumferentially as appearing at the right front end of the shaft 26 or they can be uniformly arranged as appearing at the left rear end of the shaft without interfering in the least with the mounting of the rolls thereon because said plate members are circumscribed by identical circles, hence, by the same cylinder.

It will be seen that the adjacent rolls can be placed almost in axial engagement provided that the plane of partition between them extends between a pair of adjacent plate members. Yet, upon rotation of one roll, the adjacent roll or rolls will not be affected in the least. That is, the loose relationship between adjacent plate members, provided either by the annular spacers 37 or the projections 47, will not transmit rotary motion from one roll to an adjacent roll.

Where three or more rolls are supported upon a single dispenser, as shown in FIG. 5, it may be desirable and advantageous to provide dual cutting edges 39A and 56 to facilitate manual engagement of the strips 43 of material being dispensed from the rolls 36.

Although a particular preferred embodiment of the invention has been disclosed in detail for illustrative purposes, it will be recognized that variations or modifications of the disclosed apparatus, including the rearrangement of parts, lie within the scope of the present invention.

The embodiments of the invention in which an exclusive property or privilege is claimed are defined as follows:

1. A device for rotatably and coaxially supporting plural rolls of material and for dispensing said material, said rolls having coaxial, substantially identical openings therethrough, comprising:

shaft means and means adapted to support said shaft means at spaced locations thereon;

support means rotatably supported on said shaft means for permitting a plurality of said rolls to be independently rotatably supported on said shaft means; said support means including a plurality of thin plate-like members mounted in adjacent side-by-side relationship upon said shaft means for rotation around the axis of said shaft means in planes substantially perpendicular thereto, said plate members having out-of-round peripheral edges and each peripheral edge having at least two points thereon contiguous with a circle coaxial with said axis and approximately equal in diameter to the opening in one of said rolls, the remainder of the peripheral edge of each plate member being disposed inwardly of said circle, whereby each roll can be sleeved upon one or more adjacent plate members for independent rotation relative to said shaft means; and

cutting means mounted on said support means and spaced from said support means radially of said axis for engagement by said material.

2. A device for rotatably supporting plural rolls of strip material and for dispensing pieces of said strip material, said rolls having coaxial cylindrical openings of substantially the same diameter, comprising:

base means, shaft means removably mounted upon said base means; plural, relatively thin plate members rotatably supported, one adjacent to another, upon said shaft means, the peripheral edge of each plate means being in the form of a regular polygon circumscribed by a circle concentric with said shaft and having a diameter substantially identical with the diameter of said cylindrical openings, each plate member being spaced slightly from the plate members adjacent thereto, whereby said plural rolls can be sleeved upon one or more of said plate members for independent rotation therewith;

spacing means positioned between and coacting with each pair of adjacent plate members for maintaining the adjacent plate members slightly spaced from one another; and

cutting edge means on said base means substantially parallel with said shaft means and spaced therefrom a distance substantially greater than the radii of said circumscribed circles.

3. A device according to claim 2, wherein alternate plate members along said shaft means have integral, axial projections extending from both sides thereof for defining said spacing means whereby said spacing between said adjacent plate members is effected.

4. A device according to claim 2, where said spacing means includes annular spacing members rotatably supported around said shaft means and positioned between each pair of adjacent plate members, whereby said spacing is effected.

5. A device according to claim 2, for supporting at least three adjacent coaxial rolls, wherein said cutting edge means has two parallel portions spaced from each other in a direction substantially perpendicular to a plane defined by said cutting edge and the axis of said shaft means, the strip material on at least one of said rolls being engageable with one of said edge portions and the strip material on another of said rolls being engageable with the other cutting edge portion.

6. A cutting device according to claim 2, wherein said base means includes a pair of spaced and parallel arms; and a pair of U-shaped clips, one thereof being secured to the free end of each arm for releasably engaging opposite end portions of said shaft means.

7. A device according to claim 1, further including spacing means positioned between and coacting with each pair of adjacent plate members for maintaining the adjacent plate members slightly spaced from one another.

8. A device according to claim 7, wherein said spacing means are also mounted for rotation relative to said shaft means.
